UNITED STATES PATENT OFFICE

115,233

DESIGN FOR AN OPEN MESH BAG

John E. Millett, Grand Rapids, Mich., assignor to
Sackner Bag Company, Grand Rapids, Mich.

Application August 2, 1937, Serial No. 70,773

Term of patent 14 years

To all whom it may concern:

Be it known that I, John E. Millett, a citizen of the United States, residing at Grand Rapids, in the county of Kent and State of Michigan, have invented a new, original, and ornamental Design for an Open Mesh Bag, of which the following is a specification, reference being had to the accompanying drawing, forming part thereof.

The figure is a front elevational view of a bag embodying my design.

The design is characterized by an open mesh bag of the form shown, in which the vertical strands of the mesh are uniformly spaced

throughout the entire width of the bag, and the transverse strands thereof have the same regular spacing as the vertical strands at the upper and lower portions of the body of the bag, but being relatively closely spaced at the central portion thereof thereby forming a central band in width substantially one-third of the height of the bag. The bag is flat and the opposite side is substantially the same as the side shown in the drawing.

I claim:

The ornamental design for an open mesh bag, substantially as shown and described.

JOHN E. MILLETT.
